UNITED STATES PATENT OFFICE.

NIKON LEE, OF BROOKLYN, NEW YORK, ASSIGNOR TO SEARS-CROSS COMPANY, OF BROOKLYN, NEW YORK, A CORPORATION OF NEW YORK.

GRENADE.

1,291,941.

Specification of Letters Patent. Patented Jan. 21, 1919.

Application filed July 5, 1917. Serial No. 178,553.

To all whom it may concern:

Be it known that I, NIKON LEE, a citizen of the United States, and a resident of the borough of Brooklyn, in the county of 5 Kings and State of New York, have invented certain new and useful Improvements in Grenades, of which the following is a specification, reference being made to the accompanying drawings, forming a part 10 thereof.

My invention relates more particularly to hand grenades and the principal object of my invention is, among other things, to reduce, if not altogether eliminate, the 15 danger of premature explosion due to the grenade being accidentally dropped from the hand or from any other cause. In hand grenades constructed according to my invention the spring-impelled striker for the firing mechanism is normally held in inoperative 20 position by a lever arranged externally of the body of the grenade, which lever is adapted to be held in retracted relation thereto by manually removable retaining 25 devices. When the hand has grasped the body of the grenade the lever is held in its retracted position, after the retaining devices have been removed to release the lever, by the free end of the lever resting in the hole 30 low of the hand, and the lever itself is released and flies outwardly from the grenade in the act of hurling the grenade. According to one feature of my invention I have provided a novel and improved combination 35 of safety devices which are successively and dependently actuated in throwing the firing pin into operative relationship with the spring-impelled striker thereby affording the maximum of security in the manipulation of the grenade preparatory to its hurling.

Another feature of my improved grenade is to so construct and combine the different parts comprising the grenade that the chamber for the high explosive, as well as the tubular housing for the cap, fuse and detonator, may be readily sealed and water proofed from surrounding dampness and moisture.

50 I attain these advantageous results by the grenade shown in the accompanying drawings in which—

Figure 1 is a sectional elevation of a preferred embodiment of my invention;

Fig. 2 is a top plan view of the cap and its associated devices;

Fig. 3 is a perspective view of the cap and devices shown in Fig. 2;

Fig. 4 is a detail sectional elevation of the cap with some of its devices in a different position from that shown in Fig. 1; and

Fig. 5 is an enlarged detail view taken on the line 5—5 shown in Fig. 1.

Similar numerals refer to similar parts throughout the several figures.

Referring to the drawings, 6 indicates the usual form of the hollow body of a hand grenade having the cap 7 at its lower end closing the chamber 8 for the high explosive material as shown in Fig. 1. The opposite end of the chamber 8 is closed by the rotatable cap member 9 screw-threaded at 10 and adapted to be tightly screwed in the opening 11 formed in the top of the grenade. Concentrically mounted in the cap 9 is the tubular housing 12 which is screw-threaded in the cap 9 as shown; the housing 12 extends within the chamber 8 and on its upper end the annular plate 13 is securely mounted and sealed. The plate 13 concentrically carries the percussion cap 14 which fits tightly in the plate 13 and from the cap 14 depends the time fuse 15 which is in communication with the detonator charge 16 contained in the lower end of the housing 12 as shown in Fig. 1.

The upper end of the cap 9 is preferably constructed in the form of a cylindrical hood 17 which contains within itself the striker 18 which is impelled or forced downwardly when released, by the spring 19 coiled within the striker 18 as shown in Figs. 1 and 4, one end bearing against the top of the hood 17 and the other spring end bearing on the lower end of the striker 18. The striker 18 is provided with a hammer 20 concentrically mounted on the under surface of the lower end as shown. The striker 18 is maintained in its upper or retracted position in which the coil spring 19 is under tension by the external lever 21, the inner end 22 of which is adapted to engage the lower rim 23 of the striker 18 as shown in full lines in Figs. 1 and 4. The lever 21 has the hooked fulcrum 24 providing a recess 25 for the pivot bearing 26 transversely secured across the slotted shoulder 27 upwardly extending from the cap 9 as shown. The lever 21 extends down-

ardly around the body 6 of the grenade, and its free end 28 is adapted to rest in the hollow of the hand when the grenade is grasped by the operator preparatory to hurling.

Extending transversely across the lower end of the cap 9, and integral therewith, is the tubular housing 29 open at both ends and into which is fitted the sliding bolt 30, adapted to be manually reciprocated within the housing 29. The bolt 30 carries in the vertical slot 31 the firing-pin 32 which is held in its normal retracted position as shown, by means of a fine wire 33, preferably made of copper, extending laterally through the pin 32 and through the two oppositely disposed holes 34 extending laterally through the bolt 30 as shown in Fig. 5. The right-hand end of the bolt 30 has the vertical slot 35 formed therein in which slot the lever 21 is retained in its retracted position by the split-pin 36 passing laterally through the perforations 37 in the bolt 30 and also through the hole 38 formed in the lever 21. The left-hand end of the bolt 30 has the laterally extending perforation 39 which registers with the transverse slot 40 formed in the side of the housing 29. Vertically above the middle point of the slot 40 is the perforation 41 laterally extending through the lug 42 preferably an integral part of the cap 9 as shown. 43 designates the spring latch-pin preferably constructed of lighter material than the split-pin 36 and having the two prongs 44 and 45, the upper prong 44 passing through the perforation 41 and the lower prong 45 passing through the perforation 39 and slot 40, as shown. In Fig. 1 the prong 45 is shown in its right inclined position in which the bolt 30 extends toward the right thereby holding the firing-pin 32 out of vertical alignment with the percussion cap 14 and the hammer 20; Fig. 4 shows the bolt 30 moved to its left position through the twisting of the latch-pin 43 in which the prong 45 rests at the left end of the slot 40, thereby bringing the firing-pin 30 in operative position between the percussion cap 14 and the hammer 20. It will be noted that before the bolt 30 can be moved to the position shown in Fig. 4, the split-pin 36 must be removed from its lever-retaining position shown in Fig. 1 thereby placing the perforations 37 out of alignment with the hole 38 in the lever 21 as shown in Fig. 4, the lever being then held in its retracted position only by its free end 28 bearing against the operator's hand which grasps the grenade.

In making ready the grenade for hurling, the thrower first grasps the grenade so that the lever end 28 bears against the hollow of his hand, and then the split-pin 36 is withdrawn by the other hand; in so doing the grenade often slips from the hand in

which case the lever 21 flies outwardly as shown in dotted lines in Fig. 1 releasing the spring-impelled striker 18 thereby causing the premature explosion if the firing-pin 32 were in operative position. However, it should be noted that in my improved device, should the lever 21 slip and fly outwardly to release the striker mechanism, the pin 32 is out of vertical alignment between the percussion cap 14 and the hammer 20, and no explosion could take place. However, when the split-pin 36 has been properly removed, and the lever end 28 is securely held by the hand, the operator then readily twists the latch-pin 43 from the position shown in Fig. 1 to that shown in Fig. 4 thereby shifting the bolt 30 with the firing-pin 32 to the left so as to bring the latter into operative position over the percussion cap 14 without endangering his grasp on the grenade. When the grenade is hurled, the lever 21 flies outwardly to the position shown in dotted lines in Fig. 1, thereby releasing the striker 18 which is impelled downwardly by the spring 19 as shown in dotted lines; the striker 18 drives the pin 32 on the percussion cap 14, thereby shearing off the pin-retaining wire 33, and igniting the time-fuse 15 which in turn explodes the detonator charge 16 to ignite the high explosives in the chamber 8.

It will be noted that perfect security is afforded in using my improved grenade due to the successive and depending action of the following safety-devices, first, in that the removal of the split-pin lever-retaining device which controls the action of the releasing lever may be accomplished without danger of a premature explosion because the firing-pin is out of operative alignment; and secondly in providing the latch-pin actuated sliding-bolt which not only carries the firing-pin out of operative position while the split-pin is being removed, but also allows the firing-pin to be moved into operative position at the will of the operator after he is assured that he has a firm grasp of the grenade body 6 and the lever end 28.

My grenade may be readily waterproofed and sealed in that the screw-threaded cap 9, tubular housing 12, annular plate 13, and percussion cap 14 may all be combined and fastened together so as to provide a watertight construction which has obvious advantages in trench warfare.

It will be understood that the grenade construction herein shown and described may be variously modified and changed without departing from the principle and scope of my invention, and it will be understood that the invention is not limited to any particular form except in so far as such limitations are set forth in the claims.

I claim as my invention:

1. A grenade comprising means for exploding the grenade, a striker movable in

relation thereto, and means interposed between said striker and said exploding means to discharge the latter and held normally in inoperative position but directly movable into operative position with the striker and exploding means at will.

2. A grenade comprising means for exploding the grenade, a spring-impelled striker movable in relation thereto, and means interposed between said striker and said exploding means to discharge the latter and held normally in inoperative position but directly movable into operative position with the striker and exploding means at will.

3. A grenade comprising means for exploding the grenade, a spring-impelled striker movable in relation thereto, and means interposed between said striker and said exploding means to discharge the latter and held normally in inoperative position but directly and manually movable into operative position with the striker and exploding means at will.

25 4. A grenade comprising means for exploding the grenade, a striker movable in relation thereto, and reciprocal means interposed between said striker and said exploding means to discharge the latter and held normally in inoperative position but directly movable into operative position with the striker and exploding means at will.

5. A grenade comprising means for exploding the grenade, a striker movable in relation thereto, and reciprocal means interposed between said striker and said exploding means to discharge the latter and held normally in inoperative position but directly and manually movable into operative position with the striker and exploding means at will.

6. A grenade comprising means for exploding the grenade, a striker movable in relation thereto, a lever disposed externally of the grenade to control said striker, means interposed between said striker and said exploding means to discharge the latter and held normally in inoperative position and movable into operative position with the striker and exploding means at will, and means engaging said last mentioned means to hold the lever in its striker-controlling position.

7. A grenade comprising means for exploding the grenade, a striker movable in relation thereto, a lever disposed externally of the grenade to control said striker, reciprocal means interposed between said striker and said exploding means to discharge the latter and held normally in inoperative position and movable into operative position with the striker and exploding means at will, and means engaging said last mentioned means to hold the lever in its striker-controlling position.

8. A grenade comprising means for exploding the grenade, a striker movable in relation thereto, a lever disposed externally of the grenade to control said striker, reciprocal means interposed between said striker and said exploding means to discharge the latter and held normally in inoperative position and manually movable into operative position with the striker and exploding means at will, and means engaging said last mentioned means to hold the lever in its striker-controlling position.

9. A grenade comprising means for exploding the grenade, a striker movable in relation thereto, a lever disposed externally of the grenade to control said striker, means interposed between said striker and said exploding means to discharge the latter and held normally in inoperative position and movable into operative position with the striker and firing means at will, and means engaging said last mentioned means to hold the lever in its striker-controlling position and said means in its inoperative position.

10. A grenade comprising means for exploding the grenade, a striker movable in relation thereto, a lever disposed externally of the grenade to control said striker, reciprocal means interposed between said striker and said exploding means to discharge the latter and held normally in inoperative position and movable into operative position with the striker and firing means at will, and means engaging said last mentioned means to hold the lever in its striker-controlling position and said means in its inoperative position.

11. A grenade comprising means for exploding the grenade, a striker movable in relation thereto, means disposed externally of the grenade to control the striker, means interposed between said striker and said exploding means to discharge the latter and held normally in inoperative position and movable into operative position with the striker and firing means, means for releasing said striker controlling means and said last-mentioned means from its inoperative position, and means for moving said interposed means into operative position.

12. A grenade comprising means for exploding the grenade, a striker movable in relation thereto, means disposed externally of the grenade to control the striker, means interposed between said striker and said exploding means to discharge the latter and held normally in inoperative position and movable into operative position with the striker and firing means, means for releasing said striker controlling means and said last-mentioned means from its inoperative position and means for thereafter moving said interposed means into operative position.

13. A grenade comprising means for ex-

ploding the grenade, a striker movable in relation thereto, means disposed externally of the grenade to control the striker, means interposed between said striker and said exploding means to discharge the latter and held normally in inoperative position and movable into operative position with the striker and firing means, means for releasing said striker controlling means and said last-mentioned means from its inoperative position, and means for moving said interposed means into operative position at will.

14. A grenade comprising means for exploding the grenade, a striker movable in relation thereto, means disposed externally of the grenade to control the striker, means interposed between said striker and said exploding means to discharge the latter and held normally in inoperative position and movable into operative position with the striker and firing means, means for releasing said striker controlling means and said last-mentioned means from its inoperative position, and means for thereafter moving said interposed means into operative position at will.

15. A grenade comprising means for exploding the grenade, a striker movable in relation thereto, means disposed externally of the grenade to control the striker, means interposed between said striker and said exploding means to discharge the latter and held normally in inoperative position and movable into operative position with the striker and firing means, means for releasing said striker controlling means and said last-mentioned means from its inoperative position, and means for thereafter moving said interposed means into operative position at will.

16. A grenade comprising means for exploding the grenade, a striker movable in relation thereto, means disposed externally of the grenade to control the striker, reciprocable means interposed between said striker and said exploding means to discharge the latter and held normally in inoperative position and movable into operative position with the striker and exploding means, means for releasing said striker controlling means and said last-mentioned means from its inoperative position, and means for moving said interposed means into operative position.

17. A grenade comprising means for exploding the grenade, a striker movable in relation thereto, means disposed externally of the grenade to control the striker, reciprocable means interposed between said striker and said exploding means to discharge the latter and held normally in inoperative position and movable into operative position with the striker and exploding means, means for releasing said

striker controlling means and said last-mentioned means from its inoperative position, and means for moving said interposed means into operative position at will.

18. A grenade comprising means for exploding the grenade, a striker movable in relation thereto, means disposed externally of the grenade to control the striker, reciprocable means interposed between said striker and said exploding means to discharge the latter and held normally in inoperative position and movable into operative position with the striker and exploding means, means for releasing said striker controlling means and said last-mentioned means from its inoperative position, and means for thereafter moving said interposed means into operative position at will.

19. A grenade comprising means for exploding the grenade, a spring-impelled striker movable in relation thereto, means for controlling said striker, and means interposed between said striker and said exploding means to discharge the latter and locked in inoperative position when said striker control means is locked to said interposed means, but movable into operative position when said striker-control means is released.

20. A grenade comprising means for exploding the grenade, a spring-impelled striker movable in relation thereto, means for controlling said striker, and means interposed between said striker and said exploding means to discharge the latter and locked in inoperative position when said striker control means is locked to said interposed means, but manually movable into operative position when said striker-control means is released.

21. A grenade comprising means for exploding the grenade, a striker movable in relation thereto, and means interposed between said striker and said exploding means to discharge the latter and held normally in inoperative position, but transversely movable with respect to the striker movement into operative position with the striker and exploding means.

22. A grenade comprising means for exploding the grenade, a striker movable in relation thereto, and means interposed between said striker and said exploding means to discharge the latter and held normally in inoperative position, but transversely and manually movable with respect to the striker movement into operative position with the striker and exploding means.

23. A grenade comprising means for exploding the grenade, a striker movable in relation thereto, and reciprocable means interposed between said striker and said exploding means to discharge the latter and held normally in inoperative position, but

transversely movable with respect to the striker movement into operative position with the striker and exploding means.

24. A grenade comprising means for exploding the grenade, a striker movable in relation thereto, and reciprocable means interposed between said striker and said ex-

ploding means to discharge the latter and held normally in inoperative position but transversely and manually movable with respect to the striker movement into operative position with the striker and exploding means. 10

NIXON LEE.
